Fig. 3

Fig. 4

FIG. 1 is a plan view of a soft surface floor covering embodying my new design showing a regular repeating unit;

FIG. 2 is a cross-sectional view taken along line 2—2 of FIG. 1 and viewed in the direction of the arrows;

FIG. 3 is a view of a portion of FIG. 1; and

FIG. 4 is a cross-sectional view taken along line 4—4 of FIG. 3 and viewed in the direction of the arrows.

The backing surface opposite to the surface shown in FIG. 1 is a conventional planar backing without ornamentation.

I claim:

The ornamental design for a soft surface floor covering, as shown and described.
